UNITED STATES PATENT OFFICE.

JOHN H. D. PETERSEN, OF CHICAGO, ILLINOIS, ASSIGNOR TO LINK-BELT COMPANY, OF CHICAGO, ILLINOIS, A CORPORATION OF ILLINOIS.

CHUTE FOR CONTROLLING THE DISCHARGE OF COAL FROM RECIPROCATING SCREENS.

1,314,755.

Specification of Letters Patent.

Patented Sept. 2, 1919.

Application filed July 15, 1918. Serial No. 244,874.

To all whom it may concern:

Be it known that I, JOHN H. D. PETERSEN, a citizen of the United States, residing at Chicago, in the county of Cook and State 5 of Illinois, have invented a certain new and useful Improvement in Chutes for Controlling the Discharge of Coal from Reciprocating Screens, of which the following is a specification.

10 My invention relates to means for discharging and particularly controllably discharging lump coal from the end of a reciprocating screen in such way that the coal after it has been prepared or sized will 15 reach a car with a minimum of breakage.

It will be understood that the coal is discharged from the tipple onto an inclined reciprocating screen. As the screen reciprocates the coal of varying sizes is screened 20 off and discharged into the coal cars, many different means being used to get the coal from the screen to the car. The farther down the screen the coal goes the larger proportion of the smaller sizes will be drawn 25 off until at the end of the screen we try to have and expect to have only the very large lump coal.

This lump coal must be delivered with a minimum of fines and smaller scraps and 30 because the coal is large there is a tendency for it to rush down the lower end of the screen at a relatively high velocity and means must be provided to check this high velocity and control the flow and discharge 35 of the coal but this checking means must be exceedingly gentle else the impact of the coal lumps against one another and against the screen will result in the breaking up of large pieces.

40 My invention, therefore, comprises means for catching the coal as it leaves the screen and, of course, these means may be used for catching the coal of different sizes and may be applied at different places along the 45 screen and easing the coal down toward the car and gradually changing it and discharging it along a path perpendicular to the path traveled by it on the screen.

In general terms, my invention comprises

a series of separate inclined adjacent plane 50 surfaces so arranged that the coal passes from the screen onto and across a series of these surfaces and these surfaces are so arranged that the movement of the coal in a direction parallel with the axis of the 55 screen is gradually stopped and a movement of the coal along a line inclined to the axis of the screen is gradually started. The inclined planes are so arranged that a light, small piece of coal coming down at low 60 velocity will be slowed up and deflected and the same will happen to a heavy large piece coming at high velocity, the only difference being that the large high velocity piece may come a little farther onto or across one of 65 or some of said planes before its speed has been sufficiently reduced.

In order to visualize the device, it is necessary to think of an individual piece of coal which travels along the screen down to the 70 first inclined plane which gives it a slight velocity to clear the screen then across a tilted plane. The piece of coal travels along a line parallel with the axis of the screen, being deflected downwardly on a transverse 75 line inclined to the axis of the screen, and thence the coal reaches a further plane which completes the deflection. The faster the coal is traveling the farther it goes on and across these different inclined planes. 80

When the apparatus is running at full volume, a large stream of coal is traversing the chute, and it will be impossible to trace the individual coal particles, but the effect is the same because the friction of the lower 85 particles against these different inclined planes causes them to reduce in speed and change direction and then, by this gradual reduction in speed and gradual change in direction, they gradually affect the other 90 particles of the coal, so that the whole stream of coal is controlled by the effect of these inclined planes operating on the bottom of the stream. This can be done without damage to the coal because the coal particles themselves are all in contact and they merely cause pressure upon one another and do not have sufficient play to strike or grind. 95

My invention is illustrated more or less diagrammatically in the accompanying drawings wherein:

Figure 1 is a side elevation of the screen with my chutes in position;

Fig. 2 is a top plan view of the chute itself with the discharge chute;

Fig. 3 is a side elevation of the chute and discharge chute;

Fig. 4 is an end view of the discharge chute.

Like parts are indicated by like letters in all the figures.

A is a supporting framework mounted on the columns A¹ A² which columns also carry a covering shed A³. A⁴ A⁴ are car tracks upon which travel cars A⁵ A⁵ adapted to be filled with coal or other such friable material. A⁶ is a chute which may or may not be my type of chute. I have shown it an ordinary type because it catches the finely divided part of the coal which is sold as slack or dust and which therefore does not need any particular care. This chute is mounted on the framework A and takes coal from the screen which I am about to describe the coal being allowed to drop freely from the end of the chute into the car below. A⁷ A⁷ are pivoted chutes. The way in which they are fastened to the frame is not here specifically shown because it forms no part of my invention. The free ends are adapted to be lowered in the cars A⁵ by paying out on the cables A⁸ by means of the worm and gear arrangement A⁹ and crank A¹⁰ so that the lower discharge ends of these chutes may be brought close to the bottom of the car to prevent breaking of the coal by its falling into the car. These two pivoted chutes get the coal from the screen through my special type of chute which I am about to describe.

B B are rollers mounted on the frame A. B¹ is a reciprocating screen. It is provided with a plurality of supporting lugs B² which have tracks B³ resting upon the rollers B B. B⁴ is a connecting rod leading from any suitable source of power to the screen means being provided to reciprocate it to cause the screen to reciprocate. It will be noted that the tracks B³ are horizontal and therefore inclined to the screen the screen itself being downwardly inclined thus reciprocation of the screen takes place in a direction not parallel with the axis of the screen but inclined thereto in a horizontal plane. B⁵ is a chute. It may be fixed or it may oscillate as the case may be adapted to discharge coal or other material into the screen B¹ at its upper end. B⁶ is a perforated screening floor. The perforations, it will be observed, are small so that only small particles of coal can pass through and enter the pocket B⁷ beneath the screen whence they are discharged into the chute A⁶. Farther down on the

screen is a perforated screen floor B⁸. The perforations are larger allowing larger particles of coal to pass through into the pocket B⁹ and thence to reach the chute B¹⁰ which may or may not be my preferred form of chute. Preferably it is. The particles which are so large that they do not pass through the perforations in the floor B⁸ pass into the chute B¹¹ at the end of the screen and this chute is preferable, as indicated, my form of plane surface deflector chute.

It will be understood that while I have shown only three separations there may be more or less. The screen is sharply inclined and the coal comes very rapidly. It must be checked very rapidly in a short space particularly at the end of its excursion and deflected into the path at an angle and generally a sharp angle, to its previous path, and it is here that my screen illustrated in detail in Figs. 2, 3, and 4 assumes very considerable importance.

C is a chute terminating the perforated screen B⁸, and continuing it preferably though not necessarily at the same angle and width. C¹ C¹ are side walls to guide the path of the material. Across the end of the chute C is disposed a triangular panel C², whose base is preferably the full width of the chute. This panel is inclined downwardly from the chute. Formed on the left side of the triangular panel is a quadrilateral panel C³, its longitudinal axis inclined to the end of the chute C, the panel being inclined longitudinally downward to the right, and being inclined upward laterally from the edge of the triangular panel. On the outer side of the panel, and connected with the side walls C¹ of the chute, is a panel C⁴, tilted at an angle to the panel C³, and serving as an outer wall to guide the flow of material to the lower end of the panel. At the right of the triangular panel is a second triangular panel C⁵, sloping down to its apex at the junction point with the panels C² and C³. One side is coextensive with the adjacent side of the triangular panel C², and another side extends along the continuation of the member C¹. The three panels, C², C³ and C⁵ are so disposed that the lowest point of each is at the joint C⁶, where the three meet. The material is discharged from the outer edges C⁷ and C⁸ of the panels C³ and C⁵, and is received in the chute A⁷, or conveyed away by any other suitable means not shown. It will be understood that the drawings are to be taken in a sense as diagrammatic, and that many variations in part and in arrangement thereof may be made without departing from the spirit of my invention. The panel C², for example, need not be triangular, and the shape of all the other panels may be varied. The number of the panels used may be varied, and they

need not necessarily be plane surfaces although plane surfaces are preferable. A single inclined curved surface might be made to take the place of the panel described.

5 The use and operation of my invention are as follows:

The smaller lumps of coal or of other material conveyed will escape at the point provided through the bottom of the screen, and 10 will be conveyed to the waiting cars by any suitable form of chute or conveyance, and by my form of chute, where the size of the coal or material warrants it. The larger lumps are delivered unbroken at the end of the 15 screen, to a chute which may or may not be a continuation of the screen in angle and width, but preferably is so. The angle of this chute is such as to carry the coal by force of gravity at a fairly rapid speed. 20 Conceivably the same device may be used where the material is conveyed along a horizontal chute by momentum given to it by other means. The chute is suddenly broken by an inclined panel which conveys the coal 25 downwardly at a higher angle, and thus at a more rapid rate of travel. This panel is preferably triangular, its base being formed by the end of the chute, which is preferably at right angles to the course of the chute. 30 Forming the other two sides of the triangle are other panels inclined upwardly from the edges of the first panel. Obviously, since the edges are joined to the edges of the downwardly tilted panel, they also slope downwardly along the edges of the first panel. 35 Touching the apex of the first panel, and bounded by the downward and outward edges of the other panels, is the open space through which the material is discharged. 40 The material sliding at its normal speed down the chute, crosses the first triangular panel with accelerated speed. The momentum carries it up the sides of the two inclined panels, their inclination gradually 45 reducing the speed with which the material travels forward. But as these panels also slope down to the discharge opening, and the material, as it slacks its speed of travel in the direction given it by the chute, slides 50 in the new direction, without any violent change of direction, or violent contact with any surface, and drops down into the receiving means provided. The continuation 55 of the side wall across the top of one of the panels, and the additional tilted panel along the outside edge of the other, prevents the material from escaping from its new path of travel, where a heavy load, or the momentum of a large piece would make it 60 possible. Beyond the unavoidable contact of the separate lumps, there will be no means for pulverizing or breaking the coal or other material delivered, and it will reach its destination with a minimum loss from such

causes. Obviously this process may be carried on with an almost limitless variety of disposition of panels, shape of panels, inclination of panels, or combination of plane or curved surfaces. The principles involved would in all cases be the same.

The material is intended to be carried along a longitudinal or relatively straight line chute at a comparatively low speed so that the material may be screened as it passes along the chute. The material is then to be 70 diverted from the line of flow in the chute and directed to one side as, for example, on a pile within a car or boat or other receptacle to be loaded or to be delivered to another laterally extending chute. This 75 operation must take place with a minimum tendency to break or reduce the size of the material particles or pieces. Broadly speaking, I accomplish this result by first accelerating the flow in or at the end of the chute 80 and this may be done by a downwardly inclined portion or extension of the chute bottom; and secondly, by then arresting and directing laterally such accelerated flow of material, and this may be accomplished by 85 one or more, preferably by two, inclined planes which project into the path of the material established for it by the chute and arrest the accelerated flow of the stream and then turn it to one side. Preferably these 90 two planes join the edges of the downwardly inclined accelerator section so that the lowest corner of each is adjacent to that of the other and at one side of the middle line, but between the vertical walls of the chute and 95 below the bottom of the chute where there is formed, so to speak, a discharge corner 100 over which the material flows somewhat as it descends through the opening in the bottom of a hopper, and thence flows laterally, 105 or is delivered laterally, to the receiving receptacle or chute.

I claim:—

1. The combination of a substantially longitudinal chute adapted to convey a stream 110 of material at a relatively low speed, with means for diverting said stream to a direction at an angle to its flow in the chute comprising means for accelerating the speed of flow, and means for retarding the speed of 115 flow and directing the stream into a path at an angle to its flow in the chute.

2. The combination of a substantially longitudinal chute adapted to convey a stream of material at a relatively low speed, with 120 means for diverting said stream to a direction at an angle to its flow in the chute comprising a downwardly inclined extension of the chute bottom adapted to accelerate the speed of flow, and means for retarding the 125 speed of flow and directing the stream into a path at an angle to its flow in the chute.

3. The combination of a substantially lon-

gitudinal chute adapted to convey a stream of material at a relatively low speed, with means for diverting said stream to a direction at an angle to its flow in the chute comprising means for accelerating the speed of flow, and a plane beyond said accelerating means placed at an angle to the direction of flow and in the path of such stream of material.

10 4. The combination of a substantially longitudinal chute adapted to convey a stream of material at a relatively low speed with means for diverting said stream to a direction at an angle to its flow in the chute comprising a downwardly inclined extension of the chute bottom adapted to accelerate the speed of flow and a plane beyond said accelerating section placed at an angle to the direction of flow and in the path of such stream of material.

15 5. The combination of a substantially longitudinal chute adapted to convey a stream of material at a relatively low speed, with means for diverting said stream to a direction at an angle to its flow in the chute comprising a downwardly inclined extension of the chute bottom adapted to accelerate the speed of flow and two planes beyond said accelerating section placed each at an angle to the direction of flow and in the path of such stream of material, and terminating at a point between the side walls of the chute.

20 6. The combination of a substantially longitudinal chute adapted to convey a stream of material at a relatively low speed, with means for diverting said stream to a direction at an angle to its flow in the chute comprising a downwardly inclined triangular extension of the chute bottom adapted to accelerate the speed of flow and two planes attached respectively to the outer edges of such triangular section and both at an angle

to the direction of flow and in the path of such stream of material, the lowest point of 45 the accelerating section and the two planes being between the side walls of the chute and below the bottom of the chute.

7. The combination with a downwardly inclined chute, of a plurality of deflecting discharge chutes each made up of a plurality of inclined plane surfaces arranged to receive material from the chute and deflect and discharge it away from the chute, at an angle to the axis thereof together with material guiding means connecting the main chute with the deflecting discharge chutes.

8. The combination with a downwardly inclined chute, of a plurality of deflecting discharge chutes each made up of a plurality of inclined plane surfaces arranged to receive material from the chute and deflect and discharge it away from the chute, at an angle to the axis thereof, an intermediate 60 chute connecting the main chute with each of said deflecting chutes save the last one.

9. The combination with a downwardly inclined chute, of a plurality of deflecting discharge chutes each made up of a plurality of inclined plane surfaces arranged to receive material from the chute and deflect and discharge it away from the chute, at an angle to the axis thereof, and means 70 in connection with said main chute for delivering material to the intermediate chute 75 without impeding the flow of material down the main chute.

In testimony whereof I affix my signature, in the presence of two witnesses, this 5th 80 day of July, 1918.

JOHN H. D. PETERSEN.
